DESIGN FOR A GLOVE

Evelyn Webster, Gloversville, N. Y.

Application December 4, 1936, Serial No. 66,306

Term of patent 3½ years

To all whom it may concern:

Be it known that I, Evelyn Webster, a citizen of the United States of America, residing in Gloversville, county of Fulton, and State of New York, have invented a new, original, and ornamental Design for a Glove, of which the following is a specification, reference being had to the accompanying drawing, forming part thereof, wherein,

My design is characterized by the combination on the glove as shown of short grouped ribs and wedge shaped, stitched wool trimming on the back of the glove as shown.

I claim:

The ornamental design for a glove, substantially as shown and described.

EVELYN WEBSTER.
